CLAIM

The ornamental design for a heat management unit for a hookah, as shown and described.

DESCRIPTION

FIG. 1 is a perspective view of a heat management unit for a hookah embodying the new design;

FIG. 2 is a front side elevation view thereof;

FIG. 3 is a back side elevation view thereof;

FIG. 4 is a right side elevation view thereof; and,

FIG. 5 is a left side elevation view thereof.

The broken lines in the drawings depict portions of the heat management unit for a hookah that form no part of the claimed design.

The claimed subject matter extends to the boundary but does not include the boundary.
